UNITED STATES PATENT OFFICE.

PAUL A. WAGNER, OF CARLSTADT, NEW JERSEY.

HARNESS FOR LOOMS.

SPECIFICATION forming part of Letters Patent No. 779,193, dated January 3, 1905.

Application filed December 14, 1901. Serial No. 85,976.

To all whom it may concern:

Be it known that I, PAUL A. WAGNER, a citizen of the United States, and a resident of Carlstadt, in the county of Bergen and State 5 of New Jersey, have invented certain new and useful Improvements in Harness for Looms, of which the following is a specification.

This invention relates to improvements in loom-harness; and the object of my invention 10 is to provide a new and improved loom-harness which is strong, cheap, and durable and simple in construction.

In the accompanying drawings, like letters of reference indicate like parts in all the figures.

Figures 1 to 11 are various constructions of my improved loom-harness.

The harness is of the style in which the heddles are formed of single threads extending 20 from the edges to the central line of the harness or from edge to edge.

In the drawings, A represents the caudle-warp in all the figures, and the harness is held on the caudle warps by permanent eyes formed 25 along the edges of the harness either at the ends of the heddles or between the ends of the heddles. By "permanent" eye I mean to designate or define an eye made from or out of the thread or strand from which the heddle is 30 made or another thread and having a permanent or unchangeable structure, so as to distinguish it clearly from eye formed by looping the thread around the caudle-warp and drawing the thread taut, in which latter case 35 the dimensions of said eye must evidently depend on the larger or smaller diameter of the caudle-warp and more or less on the tightness of winding of the latter or the tension in the thread.

40 The permanent or irreducible quality of the eyes or loops permit the harness to be contracted or expanded easily upon the caudle-warps in accommodating the spacing of the heddles to conform to the number and spacing 45 of the warp-threads in the loom. In the usual knitted or woven thread harness in which the eyes are formed by a bight or loop around the caudle-warp, the bights or loops tighten and grasp the caudle-warp so firmly as to prevent,

or at least seriously interfere with, the required 50 shifting thereon. My improved harness avoids this difficulty. The permanent or unchangeable quality of the eyes offers a further advantage in that by refusing to loosen or stretch they insure a definite and unchanging 55 length of heddle on each side of the shaft when in place thereon and subjected to the strains of service. For example, as shown in Fig. 1, the permanent eyes B', through which the caudle-warp A is passed, are formed by twisting 60 the thread a' one or more times at the bottom of the eye B, and the thread a may extend from one heddle to the next, as shown at b'.

As shown in Fig. 2, the eyes B² are formed by crossing the thread a² at the bottom of the 65 eye B² and applying some adhesive substance d² at the crossing to hold the crossed parts of the threads together.

As shown in Fig. 3, the eyes B³ are formed by knotting the threads a³ directly below the 70 eye, as at g³.

As shown in Fig. 4, the eyes b⁴ are formed by uniting the threads a⁴ directly below the eye by means of a metal or other clip C⁴.

Fig. 5 shows the arrangement of a series of 75 heddles upon a pair of shafts M M. This harness is of the form shown in Fig. 1.

As shown in Fig. 6, the eye may be formed by the part e⁶ of the heddle-thread extending 80 from one heddle to the other, the eye being formed and held by a cord or thread F⁶, wrapped around the adjacent heddle-threads permanently and, if desired, extending from one heddle to the next.

As shown in Fig. 7, the threads a⁷, forming 85 the heddles, are carried at the edge of the harness from one heddle to the next, and a strand F⁷ of silk, thread, or fine wire is wound around that part of the heddle-thread extending from one heddle to the next, so as 90 to hold the ends of the heddles in place, and part of this strand F⁷ of silk, wire, or thread is bent to form permanent loops or eyes B⁷, through which the caudle-warps can be passed.

As shown in Fig. 8, the strands F⁸ can also 95 be wound around the two threads of the heddles for a greater or less length and need not be wound around the parts connecting the

heddles; but the permanent eyes B^8 are also formed by such strands on the ends of the heddles.

As shown in Fig. 9, the heddle-threads extend to a binder-thread J and are secured on the same by winding a fine strand F^9 of silk, wire, or thread around the closed ends of the heddles and the binder J , and the permanent eyes B^9 are formed on the binder J , which is looped to form such eyes, which are made permanent by the strands F^9 , wound around parts of the heddles and the binder.

As shown in Fig. 10, the strands F^{10} are wound around the binder J^2 , and the closed ends of the heddles and the eyes B^{10} are formed in and by said strands.

As shown in Fig. 11, the eyes B^{11} are formed by making a double loop or eye out of the heddle-thread a^{11} , and these eyes or loops are then made permanent by applying on them a solution of rubber, glue, or the like, as represented by m .

In all constructions shown and described the eyes by which the harness is held on the caudle-warp A are permanent and cannot be increased or decreased in size by pulling strains, and they are not dependent in their size upon the size of the caudle-warps.

Having described my invention, what I claim as new, and desire to secure by Letters Patent, is—

1. A continuous harness of thread having permanently-formed or unchangeable loops or eyes on its outer edges or margins, in combination with caudle-warps received in said loops or eyes.

2. A harness, composed of heddles the upper and lower portions formed each of a continuous thread looped at the margin to form a closed permanent eye for each heddle, in combination with a caudle-warp for each margin received in said eyes.

3. A continuous harness of thread having eyes or loops on its outer margin or margins, said loops or eyes being permanently held in proximity to the bottoms thereof, in combination with caudle-warps received in said loops or eyes.

Signed at Carlstadt, in the county of Bergen and State of New Jersey, November 16, 1901.

PAUL A. WAGNER.
